UNITED STATES PATENT OFFICE.

ALONZO M. BUCHANAN, OF MOBERLY, MISSOURI.

DESIGN FOR A MONUMENT.

Specification forming part of Design No. **10,088**, dated July 3, 1877; application filed June 4, 1877.
[Term of Patent 7 years.]

To all whom it may concern:

Be it known that I, ALONZO M. BUCHANAN, of Moberly, in the county of Randolph and State of Missouri, have originated a Design for Head-Stones or similar Monuments; and I do hereby declare that the following is a full, clear, and exact description thereof, reference being had to the accompanying photographs, which form a part of this specification.

A represents the head-stone or monumental stone, which may be of any suitable shape or configuration, and rests upon a base, B. C is a central medallion for the inscription of the name and date, &c.; and this consists of an oval shield, surrounded by a cord, c, represented as passing through loops or perforations b, made in projecting parts of the shield on four sides thereof, and terminating in two tassels, a a, one on each side of the projection

b', within which the cords are supposed to cross each other.

What I claim as my invention is—

The design for a medallion for head-stones and other monuments, consisting of a central raised shield, C, having projections b b', and surrounded by an ornamental cord, c, represented as passing through said projections, and having its ends crossed within the lowermost of these, substantially as described, and shown in the accompanying photograph.

In testimony that I claim the foregoing as my own I have hereto affixed my signature in presence of two witnesses.

ALONZO M. BUCHANAN.
